UNITED STATES PATENT OFFICE.

GUSTAVUS MARX, OF PAWNEE, OKLAHOMA.

ELECTRIC-LIGHT FIXTURE.

1,238,549.

Specification of Letters Patent. Patented Aug. 28, 1917.

Application filed December 12, 1914. Serial No. 876,902.

To all whom it may concern:

Be it known that I, GUSTAVUS MARX, a citizen of the United States, residing at Pawnee, in the county of Pawnee and State of Oklahoma, have invented new and useful improvements in Electric-Light Fixtures, of which the following is a specification.

This invention relates to light fixtures and more particularly to electric drop lights. 10 The principal object of the invention is to provide a fixture constructed in such manner that the lights may be raised or lowered so as to be held in any adjusted position, thereby obviating the use of flexible cords on 15 table lamps and like devices and combining in one device a ceiling fixture and drop light.

Another object of the invention is to provide an electrical drop light in which the 20 continuity of the electrical conductors is uninterrupted and maintained in such condition independently of the adjustment of the lights relative to the ceiling.

Further objects of the invention will appear as the following description is read in connection with the accompanying drawings, which form a part of this application and in which:—

Figure 1 is an elevation showing the device attached to the ceiling.

Fig. 2 is a vertical sectional view taken on the line 2—2 of Fig. 4.

Fig. 3 is a similar sectional view taken at right angles to Fig. 2.

Fig. 4 is a horizontal sectional view taken on the line 4—4 of Fig. 2.

Fig. 5 is a similar sectional view taken on the line 5—5 of Fig. 2.

Fig. 6 is a top plan view of the device removed from the ceiling.

Fig. 7 is a detail perspective view of one of the locking dogs.

In the specific embodiment of the invention, as illustrated herein, 1 and 2 represent the separate sections of the casing which may be, as will be readily understood, of any suitable sectional outline and which are shown to be substantially rectangular with the diagonally opposite corners of the section 1 cut away to pass the locking plates 3 arranged in diagonally opposite corners of the section 2 and having apertures 3^a arranged at intervals therein. The section 1 telescopes with the section 2 and, as shown, 55 carries the light-supporting arms 4, two only of which have been shown herein. These

light-supporting arms carry the circuit wires 5 and 6 and have suitable nipples 7 to which the lamp sockets and globes may be connected.

Secured in the bottom of the tubular casing 1 is a block of insulation 8 having channels 9 therein for the passage of the wires 5 and 6. These blocks are also provided with sockets 10 adapted to receive the rectangular heads 11 of the guiding tubes 12. These guiding tubes extend throughout the length of the lower section 1 of the casing and are provided upon their upper ends with external collars 13, the function of which will be hereinafter described. The tubes are held in place by a cap plate 14 which fits the tubes 12 and bears against the upper side of the heads 11. These cap plates, as shown, are provided with apertures 15 which register with the channels 9 so as to permit passage of the conductor wires.

Mounted in the upper end of the upper section 2 is a block 16 preferably of insulated material having apertures 17 running therethrough in spaced relation and also provided with sockets 18 in which the caps 19 are placed. These caps have threaded thereinto the rods 20 which have a length equal to the section 2 and are adapted to telescope into the tubes 12. The caps are held against rotation by having a lateral rib 21 which engages in recesses formed in the walls of the sockets 18 and are held against vertical movement by the cap plate 22 secured thereto by the bolts 23 which pass through the blocks 16 and plate 22 and secure the ceiling hanger 23 to the upper section; this hanger being concealed by the ceiling cap 24.

The conductors 5 and 6 pass directly through the plate 22 and through each cap 19 and are secured in any suitable manner as by a set screw or binding post 25 mounted upon the plate 22. After passing through the caps 19, the wires are wound around the guide rods 20 in spiral form and pass through the collars 13 on the upper end of the tube 12 where they pass directly down along side of the tube and are secured in any suitable manner to the lower ends thereof. The conductor wires are preferably insulated in the usual manner but if the tubes and rods are properly insulated one from the other, it may be found desirable to use uninsulated or bare conductors.

Threaded into the caps 19 are tubes 26

which surround and are spaced from the guiding rods 20 so as to permit the contraction and expansion of the coils of the conductor wires 5 and 6 as shown. These tubes 5 extend the full length of the section 2 and are guided in their movements by the collar 13. The tubes 26 are employed to confine the coils of the conductor wires 5 and 6, which rest upon the collars 13 and upon 10 the caps 19 when in contracted position and fit closely around the rod 20 when in extended position, the tubes 26 being of sufficient diameter to accommodate the transverse expansion of the coils when contracted. 15 Extending across the cut off corners of the lower section 1 are axles 27 and 28 which are arranged in parallelism and in the same plane and have journaled thereon the locking dogs 29 beveled upon their outer face as 20 shown at 30 provided with a slot 31 in the inner end to receive the cross pin 32 bridging the bifurcation in the upper end of the actuating rod 33. This rod passes down centrally through the lower section 1 of the 25 casing and has bearing in the block 8 and plate 14, the former serving as an abutment for a spiral spring 34 which surrounds the rod and normally holds the same depressed and the locking dogs extended, the lower 30 end of the spring bearing upon an actuating bar or head 35, which is threaded upon the lower end of the rod and passes through the finishing cap 36. The upper end of the rod 33 is guided in its movement by a 35 spider 37 extending across the upper section and having a central eye 38 formed therein. The upward movement of the rod 33 is limited by the extent of contraction of the spring 34, while its downward movement is limited by a collar 39 secured to the 40 rod and arranged to engage on the upper side of the plate 14. The upward movement of the lower section 1 is limited by the extent of contraction of the coils of the 45 conductor wires 5 and 6, while the downward movement is limited by a stop 40 arranged in one of the tubes 26 and adapted to contact with the under side of its associated collar 13.

50 In the operation of the device it will of

course be understood that the dogs 29 engage within the apertures 3^a of the locking plates 3 and when it is desired to lower the section 1, the rod 33 is pushed upwardly against the tension of the spring 34 so as to 55 release the dogs from these apertures. The section 1 may then be pulled downwardly to any desired degree and upon release of the rod 33 the dogs will engage in the next lower aperture and will lock the section 1 60 against further downward movement. The section 1 can be raised without manipulating the rod 33 as the inclined face 30 on the dogs will act as a cam which will ride over the end walls of the apertures 3^a and raise 65 the rod 33 against the tension of the spring 34. In elevating the section 1 within the section 2, the collars 13 force the conductors 5 and 6 into coils which are just accommodated by the wall of the tubes 26, the 70 rods 20 being guided within the tubes 12 and the tubes 12 being guided within the tubes 26. Internal shoulders are preferably provided adjacent the ends of each section so as to limit the inward movement 75 of the plate 14 and block 16.

What is claimed is:

A light fixture comprising a casing composed of two slidably connected sections, the outer of which having a plurality of longitudinally arranged apertures, a block of insulation mounted in each section, a pair of tubes telescoping with each other and supported respectively by the blocks of insulation, an electric conductor housed within the 80 tubes, a pair of slotted dogs pivotally supported by the inner section and adapted to engage said apertures, a rod having a portion mounted in the slots of said dogs and having one end projecting exteriorly of one 85 of said sections, said projecting end being enlarged, and a coil spring encircling said rod and abutting the block in the inner section and said enlarged end.

In testimony whereof I affix my signature 95 in presence of two witnesses.

GUSTAVUS MARX.
